UNITED STATES PATENT OFFICE

144,456

DESIGN FOR A HANDBAG OR SIMILAR ARTICLE

Clifford A. Furst, New York, N. Y.

Application December 21, 1945, Serial No. 124,930

Term of patent 3½ years

(Cl. D87—3)

To all whom it may concern:

Be it known that I, Clifford A. Furst, a citizen of the United States of America, residing in New York, county of New York, and State of New York, have invented a new, original, and ornamental Design for a Handbag or Similar Article, of which the following is a specification, reference being had to the accompanying drawing, forming part thereof.

Fig. 1 is a perspective view of a handbag or similar article, showing my new design.

Fig. 2 is a perspective view of the handbag as shown in Figure 1, with the outer cover removed.

Fig. 3 is a perspective view of the cover portion of the handbag with the handbag removed. The opposite sides of the handbag are substantially the same as the sides shown.

I claim:

The ornamental design for a handbag or similar article, substantially as shown and described.

CLIFFORD A. FURST.
